UNITED STATES PATENT OFFICE.

CLARENCE E. KELLY, OF ANDERSON, INDIANA, ASSIGNOR OF ONE-HALF
TO WILLIAM H. FORSE, JR., OF ANDERSON, INDIANA.

SPEED-INDICATOR-OPERATING MEANS.

SPECIFICATION forming part of Letters Patent No. 716,721, dated December 23, 1902.

Application filed November 14, 1901. Serial No. 82,204. (No model.)

To all whom it may concern:

Be it known that I, CLARENCE E. KELLY, a citizen of the United States, and a resident of Anderson, in the county of Madison and State 5 of Indiana, have invented a new and Improved Speed-Indicator-Operating Means, of which the following is a full, clear, and exact description.

This invention relates to a means for operating a speed-indicator. It may be used to indicate the distance traveled by a vehicle in a stated time, or it may be fitted to show the number of revolutions per minute of a turning part.

15 This specification is a specific description of one form of the invention, while the claims are definitions of the actual scope thereof.

Reference is to be had to the accompanying drawings, forming a part of this specification, 20 in which similar characters of reference indicate corresponding parts in all the views.

Figure 1 is a face view of the invention with parts broken away. Fig. 2 is a section on the line 2 2 of Fig. 1. Fig. 3 is an elevational 25 view showing the cover-plate removed, and Fig. 4 is a fragmentary section on the line 4 4 of Fig. 1.

a indicates a rotary shaft, to which my invention is here shown as applied and from 30 which it derives its movement. b indicates a casing keyed to turn with the shaft. The casing b has a cover-plate c, formed with a rabbet-groove on its periphery, in which groove are engaged the heads of screws b', fastened 35 to the casing b, thus holding the cover-plate c on the casing, so that it may be turned around the axis of the shaft a independently of the casing for the purpose of adjusting the plate, as will be fully described hereinafter. The 40 casing b has a hub b², which fits on the shaft a, and d indicates a disk which fits loosely around this hub b² outside of the cover-plate c. The disk d has pins d' attached rigidly thereto, such pins passing through the cover-45 plate c into the casing b. It will be observed, therefore, that the adjustment of the cover c carries with it a like movement of the disk d and pins d'.

Fastened to or formed integral with the 50 back wall of the casing b and located within said casing are radial guideways e. In these

guideways are respectively arranged spherical weights e', which are movable through the guideways to and from the axis of the shaft a. These weights e' are adapted to be 55 actuated by centrifugal force, and the guideways e are longitudinally slotted to receive loosely the arms f' of segmental cams f. The cams f are mounted to turn on pins f², carried by the cover-plate c in parallelism with 60 the shaft a, and the working faces f⁴ of the cams (see Fig. 3) are disposed spirally around the axes of the pins f². Spring-pressed plungers f³ are carried by the peripheral wall of the casing b radially of the shaft a and engage with the arms f', pressing the same inward. The pins d', which are fastened to the disk d and project loosely through the cover-plate c, respectively engage the working faces f⁴ of the segmental cams f. As the 70 shaft a turns its motion acts on the spherical weights e', tending to throw them outward in their guideways e. The movement of these weights is transferred to the arms f', and the cams f are caused to turn around their pivot- 75 pins f². These cams in turning ride their working faces f⁴ on the pins d' and push the pins outward, these pins carrying with them the disk d.

g indicates a rock-shaft held in a suitable 80 support g' and carrying an arm g², which has a roller g³ running on the disk d. As the disk d moves in and out under the action of the varying speed of the shaft a the shaft g is rocked, and the movement of this shaft is 85 communicated to an indicating device, whereby to show the exact speed at which the part a is moved.

It will be observed that by adjusting the cover c around the axis of the shaft a the 90 cams f, arms f', and pins d will be moved with the cover, and the axes around which the arms f' swing will be advanced to or retracted from the respective spherical weights e'. This increases or decreases the leverage 95 of the arms, and by this means the apparatus may be adjusted to the gear of the rotary element to which it is attached or to other conditions of its use.

Having thus described my invention, I 100 claim as new and desire to secure by Letters Patent—

1. The combination of a rotary carrier formed in two relatively adjustable parts normally turning as one, a centrifugally-actuated member carried by one part of the carrier, a member actuated from the centrifugally-actuated member and carried by the other part of the carrier, and means for transmitting the movement of said member which is actuated from the centrifugally-actuated part whereby upon the relative adjustment of the parts of the carrier the action of the device may be regulated. 10
2. The combination of a carrier formed in two relatively adjustable parts normally turning as one, a centrifugally-actuated weight carried on one part of the carrier, an arm pivotally sustained on the other part of the carrier and engaged by the weight, and means for transmitting the movement of the arm whereby upon the relative adjustment of the parts of the carrier the action of the device may be regulated. 15
3. The combination of a carrier formed in two relatively adjustable parts normally turning as one, a centrifugally-actuated weight carried on one part of the carrier, a cam pivoted to the other part, an arm carried on the cam and engaging the weight, and means for transmitting the movement of the cam whereby upon the relative adjustment of the parts of the carrier the action of the device may be regulated. 20
4. The combination of a carrier formed in two relatively movable parts, a centrifugally-actuated weight carried on one part of the carrier, a cam pivoted to the other part, an arm carried on the cam and engaging the weight, and means for transmitting the movement of the cam, said means consisting of a disk turning with the carrier and a pin carried by the disk and engaged by the cam. 25
5. The combination of a rotary carrier formed in two relatively adjustable parts normally turning as one, and speed-indicator-operating devices carried partly on one part of the carrier and partly on the other part of the carrier, whereby upon the relative adjustment of said parts of the carrier the parts of the speed-indicator-operating devices may be adjusted, for the purpose specified. 30
6. The combination of a rotary carrier formed in two relatively adjustable parts normally turning as one, centrifugally-actuated speed-indicator-operating devices carried partly on one part of the carrier and partly on the other part of the carrier, whereby upon the relative adjustment of the parts of the carrier the parts of the speed-indicator-operating devices may be adjusted, for the purpose specified. 35
7. The combination of a rotary carrier, comprising a body and a relatively adjustable cover-plate, a centrifugally-actuated weight on the body of the carrier, a cam on the cover-plate of the carrier and driven by the weight, and means on the cover-plate for transmitting the movement of the cam. 40
8. The combination of a rotary carrier, comprising a body and a relatively adjustable cover-plate, a centrifugally-actuated weight on the body of the carrier, a cam on the cover-plate of the carrier, and means on the cover-plate for transmitting the movement of the cam, the said cam comprising a cam proper and an arm attached thereto and engaging the weight. 45
9. The combination of a rotary carrier, comprising a body and a relatively adjustable cover-plate, a centrifugally-actuated weight on the body of the carrier, a cam on the cover-plate of the carrier, and means on the cover-plate for transmitting the movement of the cam, the said cam comprising a cam proper with a working face turning spirally around its axis and an arm attached to the cam and engaging the weight. 50
10. The combination of a rotary carrier, comprising a body and a relatively adjustable cover-plate, a centrifugally-actuated weight on the body of the carrier, a cam on the cover-plate of the carrier, means on the cover-plate for transmitting the movement of the cam, the said cam comprising a cam proper and an arm attached thereto and engaging the weight, and spring-actuated means for engaging the arm to hold it in normal position. 55
11. The combination of a rotary carrier, comprising a body and a relatively adjustable cover-plate, a centrifugally-actuated weight on the body of the carrier, a cam on the cover-plate of the carrier, means on the cover-plate for transmitting the movement of the cam, the said cam comprising a cam proper and an arm attached thereto and engaging the weight, and spring-actuated means for engaging the arm to hold it in normal position, the spring-actuated means comprising a pin mounted in the body of the casing and engaging the arm and a spring pressing the pin. 60
12. The combination of a rotary carrier, a centrifugally-actuated part thereon, a cam pivoted on the carrier and having a working face turning spirally around the axis of the cam, said cam being actuated from the centrifugal part, and means for transmitting the movement of the cam. 65
13. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam. 70
14. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam, the said means for transmitting the movement of the cam comprising a pin engaging the cam, and means for mounting the pin, such means being adjustable relatively to the cam. 75
15. The combination of a rotary carrier, comprising a body and a relatively adjustable cover-plate, a centrifugally-actuated weight on the body of the carrier, a cam on the cover-plate of the carrier, and means on the cover-plate for transmitting the movement of the cam, the said cam comprising a cam proper and an arm attached thereto and engaging the weight. 80
16. The combination of a rotary carrier, comprising a body and a relatively adjustable cover-plate, a centrifugally-actuated weight on the body of the carrier, a cam on the cover-plate of the carrier, and means on the cover-plate for transmitting the movement of the cam, the said cam comprising a cam proper with a working face turning spirally around its axis and an arm attached to the cam and engaging the weight. 85
17. The combination of a rotary carrier, comprising a body and a relatively adjustable cover-plate, a centrifugally-actuated weight on the body of the carrier, a cam on the cover-plate of the carrier, means on the cover-plate for transmitting the movement of the cam, the said cam comprising a cam proper and an arm attached thereto and engaging the weight, and spring-actuated means for engaging the arm to hold it in normal position. 90
18. The combination of a rotary carrier, comprising a body and a relatively adjustable cover-plate, a centrifugally-actuated weight on the body of the carrier, a cam on the cover-plate of the carrier, means on the cover-plate for transmitting the movement of the cam, the said cam comprising a cam proper and an arm attached thereto and engaging the weight, and spring-actuated means for engaging the arm to hold it in normal position, the spring-actuated means comprising a pin mounted in the body of the casing and engaging the arm and a spring pressing the pin. 95
19. The combination of a rotary carrier, a centrifugally-actuated part thereon, a cam pivoted on the carrier and having a working face turning spirally around the axis of the cam, said cam being actuated from the centrifugal part, and means for transmitting the movement of the cam. 100
20. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam. 105
21. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam. 110
22. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam. 115
23. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam. 120
24. The combination of a rotary carrier, a centrifugally-actuated part, a cam mounted to turn on the carrier and having a working face disposed spirally around the axis of the cam, an arm attached to the cam and engaging the centrifugally-actuated part, and means for transmitting the movement of the cam, the said means for transmitting the movement of the cam comprising a pin engaging the cam, and means for mounting the pin, such means being adjustable relatively to the cam. 125
25. The combination of a rotary carrier, comprising a body and a relatively adjustable cover-plate, a centrifugally-actuated weight on the body of the carrier, a cam on the cover-plate of the carrier and driven by the weight, and means on the cover-plate for transmitting the movement of the cam. 130

15. The combination of a rotary carrier, comprising a body part, and a cover-plate relatively adjustable thereon, a cam mounted to turn on the cover-plate of the carrier and having a working face extending spirally around the axis of the cam, a centrifugally-actuated part mounted on the body of the carrier, an arm attached to the cam and engaging the centrifugally-actuated part, and means on the cover-plate for transmitting the movement of the cam.
16. The combination of a rotary carrier, comprising a body part and a cover-plate relatively adjustable thereon, a cam mounted to turn on the cover-plate of the carrier and having a working face extending spirally around the axis of the cam, a centrifugally-actuated part mounted on the body of the carrier, an arm attached to the cam and engaging the centrifugally-actuated part, and means on the cover-plate for transmitting the movement of the cam, the said means on the cover-plate comprising a pin mounted to slide therein and a disk located outside of the carrier and attached to the pin.
17. The combination of a rotary carrier, a cam mounted thereon, a centrifugally-actuated part mounted on the carrier and actuating the cam, and a spring-pressed pin carried in the peripheral walls of the carrier and serving to return the cam to normal position.
18. The combination of a rotary carrier, a centrifugally-actuated part mounted thereon, a cam mounted on the carrier, an arm attached to the cam and bearing on the said centrifugally-actuated part, and a spring-pressed pin carried in the peripheral walls of the carrier and engaging the arm of the cam, whereby to return the cam to normal position.
19. A speed - indicator - operating means, comprising a rotary carrier, walls thereon forming a passage-way extending outward from the central part of the carrier, said walls having a slot therein, a weight mounted in the passage-way, and means for transmitting the movement of the weight, said means including a part projected through the slot in the said walls of the passage-way and bearing against the weight.
20. A speed - indicator - operating means, comprising a rotary carrier, walls thereon forming a passage-way extending outward from the central part of the carrier, said walls having a slot therein, a weight mounted in the passage-way, means for transmitting the movement of the weight, said means including a part projected through the slot in the said walls of the passage-way and bearing against the weight.
21. The combination of a rotary casing forming a carrier, centrifugally-actuated devices in the casing, a pin extending through a wall of the casing and engaging said centrifugally-actuating devices to transmit the movement thereof, and a disk mounted on the outside of the casing and fastened to the pin.
22. The combination of a carrier, comprising two parts relatively adjustable for the purpose specified, a centrifugally-actuated weight on one part of the carrier, and means for transmitting the movement of the weight, said means being carried on the other part of the carrier.
23. The combination of a carrier, comprising two parts relatively adjustable for the purpose specified, a centrifugally-actuated weight on one part of the carrier, means for transmitting the movement of the weight, said means being carried on the other part of the carrier, and comprising a pivoted cam, an arm attached to the cam and engaging the weight, and a member bearing against the cam to be actuated thereby.
24. The combination of a rotary carrier, means mounted within the same, said means being movable by centrifugal force and comprising a part projected through one wall of the carrier to the outside thereof, and an annulus located outside of the carrier and connected with said projected part, said annulus being movable axially and serving to transmit the movement of said projecting part.
- In testimony whereof I have signed my name to this specification in the presence of two subscribing witnesses.
- CLARENCE E. KELLY.
